BOILER STAND

William Zeller Davis, Niles, Ohio

Application October 9, 1934, Serial No. 747,526

2 Claims. (Cl. 248—163)

This invention relates to supporting devices for receptacles such as range boilers. More particularly the invention relates to a stand or support for range boilers which are manufactured with an annular flange about the lower end of the boiler.

In supports of prior construction difficulties arose through insufficient strength due to structural arrangement, to a lack of rigidity in the related parts, and also through inability to adjust the support relative to the boiler and floor.

It is an important object of the present invention to provide a support or stand for flanged boilers which may be rigidly maintained in position in relation to the boiler which in addition has adequate structural strength with a minimum of parts, and which moreover is capable of adjustment not only horizontally but also vertically so that the boiler weight is uniformly distributed on the floor without strain on the plumbing connections to the boiler.

With the above objects in mind reference may be now made for a complete disclosure of my invention to the following description and accompanying drawing in which:

25 Fig. 1 is a view in perspective of the stand applied to a range boiler;

Fig. 2 is an elevation of the stand in position within the lower flange of the boiler; and

30 Fig. 3 is a plan view of the stand showing the various adjusting means.

For purposes of illustration I have shown the stand 10 as applied to the base of a cylindrical boiler or tank 11, known in the trade as a range boiler.

35 These boilers are ordinarily formed with an annular base flange 12 at the juncture of the base plate 13 and the boiler wall 14.

I provide a ring 1 made preferably of strap or band metal which is adapted to be positioned with the strap in vertical position within and adjacent the flange 12. This ring 1 is maintained in rigid relationship with the flange 12 by means of three set screws 3 which may be adjusted to accommodate the ring to flanges of different diameter. The ring is supported by three legs 2. Each of these legs consists of an angle bar, a face of the upper end of each bar being welded or otherwise attached to the ring 1. One of these legs is provided with a vertical adjustment 4 consisting of a square nut 15 secured to the two walls of the angle bar of the leg and adapted to receive the adjustment screw 16. The head 17 of the screw forms the contact base of the leg with the floor and vertical adjustment of the stand 10 may 55 thereby be made.

In utilizing the boiler stand as above described, a boiler of the type mentioned having a base flange is mounted vertically on the stand with the ring 1 within the base flange. The set screws 3 are then adjusted until they contact against the boiler flange, the stand in this manner becoming fixed relative to the boiler. Should the boiler be out of vertical or should it be necessary to move the boiler in relation to vertical on account of plumbing attachments, the head 17 of the screw 16 may then be adjusted until the proper position of the boiler is secured.

The stand as above described has several features which have been found to be of value and recognized utility. By using a band or ring 1 with a vertical edge and with the legs 2 positioned directly below the ring in the line of ring edge pressure the maximum strength and resistance against deformation is obtained. Hence the amount of metal required for the stand is reduced.

Further the use of angle iron in the legs 2 by reason of the right angled distribution of metal gives added strength and rigidity to the stand and makes possible the elimination of reinforcing rods which are usually provided to connect the legs of a support stand to prevent spreading thereof.

Finally the plural adjustment both vertical and lateral makes possible a solid positioning of the boiler on the floor without strain. Particularly the vertical adjustment 4 with the two-walled support for the nut 15 adds to the utility of the stand.

While the preferred embodiment of the invention has been shown and described I do not desire to be limited to the precise disclosure except insofar as required by the claims hereto appended.

What I claim is:

1. A support for a boiler having a flanged base, comprising a ring formed of strap metal, legs formed of angle iron, each leg being secured at one end to said ring, and means to adjustably position said ring relative to and within said flanged base, one of said legs having means for adjusting the effective length thereof.

2. A support for a boiler having a flanged base, comprising a continuous non-extensible ring formed of strap metal, legs formed of angle iron, each leg being secured at one end to said ring, means manipulated within the ring to adjustably position said ring relative to and within said flanged base, one of said legs having means for adjusting the effective length thereof.
